CALORIE CALCULATOR

Henry Leiser, Denver, Colo.

Application June 2, 1950, Serial No. 165,741

2 Claims. (Cl. 235—83)

1

This invention relates to what might be termed a calorie totaler. People on a diet, either for weight reducing or health purposes, endeavor to total their calorie intake during the day so as not to exceed a certain daily pre-set maximum. This is a difficult procedure, since it involves checking with a chart for each particular food to determine the caloric content of each specific food, and then it necessitates recording the calories as consumed and constantly totaling the recorded calories to determine whether the pre-set maximum has been exceeded.

The principal object of this invention is to provide a neat, simple device which can be carried in a pocketbook, handbag, or pocket, and which will not only serve as an index for the caloric content of various foods, but will automatically total and indicate the total of the calories consumed during any given period.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a perspective view illustrating the improved calorie totaling device as it would appear in use;

Fig. 2 is a top view thereof; and

Fig. 3 is a longitudinal section, taken on the line 3—3, Fig. 2.

The improved calorie totaling device is mounted on a backing card 10 having a pivot rivet 11 at one extremity. A front card 12 overlies the backing card 10 and is preferably, but not necessarily, spaced therefrom by means of a spacer sheet 13.

The front card 12 is similar in contour to the backing card 10, and the two cards and the spacer sheet 13 are glued or otherwise permanently secured together. The members 10, 12, and 13 may be formed from any suitable sheet material, such as cardboard, Celluloid, or sheet plastic.

A calculating disc 14 is rotatably mounted on the rivet 11 between the cards 10 and 12. The disc 14 projects for substantially one-half its area beyond the extremity of the members 10 and 12 and is imprinted with a calorie scale reading counter-clockwise from zero to any chosen total, preferably the largest expected total of calories

to be consumed by a normal person during a twenty-four hour period.

As illustrated, the scale 15 is indexed to read from zero to 4000 calories in one-hundred-calorie intervals. A pointer, preferably of transparent plastic, having an indicating arm 16 and a setting arm 17, is pivotally mounted on the upper extremity of the rivet 11 over the top card 12. An indicating line 18 extends through the length 10 of the pointer and intersects the axis of the rivet 11.

The setting extremity 17 of the pointer passes beneath a plurality of leaves or pages 19 which are hingedly bound together and to the top card 15 12 by means of any suitable binding devices 20. Each of the pages 19 is imprinted to present a columnar list for a class of food. For instance, one of the pages may be imprinted "meats" and will contain a list of various meats, such as indicated at 21. From each of the meats listed on the list 21 a leader line 22 extends to a predetermined point on the right-hand edge of that page 19. The same procedure is followed on the other pages 19, each of which contains a separate list 25 of foodstuffs, such as "cereals," "breads and "pastries," "vegetables," "desserts," "drinks," etc. All of the pages contain the leader lines 22 extending to predetermined positions at the right-hand edge of the page.

The device is used as follows: the disc 14 is rotated to place the "zero" marking opposite the edge of the top card 12, as shown in Fig. 2. The pages 19 are turned to the proper class of food to be eaten, for instance "meats." The pointer is turned until the black line 18 on the setting arm 17 thereof intersects the extremity of the leader line 22, leading from the chosen meat. The indicating arm 16 of the pointer and the edge of the disc 14 are now gripped between the thumb and forefinger to lock them together, as shown in Fig. 1. They are then both swung downwardly and to the left until the setting arm 17 strikes a stop device 23 projecting upward from the top card 12. This swings the "zero" indication to the right a distance proportionate to the caloric content of the chosen meat.

The pages 19 are now turned to the next class of food to be eaten, such as "desserts," and the setting arm 17 is swung to intersect the extremity 50 of the leader line 22 of a selected "dessert," as shown in Fig. 2. The pointer and the disc are again gripped between the thumb and forefinger and swung downwardly to the left as before. This totals the calories of the selected dessert 55 with the calories of the consumed meat. This

procedure is continued throughout the meal or throughout the day. The user can always glance at the intersection of the front edge of the top card 12 with the index scale 15 and immediately note the total number of calories which have been consumed since the original "zero" setting was made.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. A calorie totaler comprising: a backing card; a front card mounted on said backing card; a calculating disc provided with a peripheral series of graduations positioned between both cards; an index edge on said front card over said graduations and against which said graduations may be read; a pivot member rotatably mounting said disc to said cards, said disc projecting for substantially one-half its area beyond the extremities of the cards; a pointer mounted on said pivot member and extending oppositely outward from the latter over both sides of said disc; a plurality of pages hingedly bound to said top card and adapted to overlie one extremity of said pointer and one edge of said disc, each of the pages being imprinted with a columnar list with which the extremity of the pointer may be aligned; and a stop member projecting from said front card into the path of said pointer to stop the latter at a predetermined point.

2. A calorie totaling device comprising: a relatively rigid card; a plurality of pages hingedly mounted on the front face of said card at one extremity thereof and overlying the latter, said

5 pages being imprinted to present a columnar list of foods with a leader line extending from each food indication; a pivot member at the other extremity of said card; a calculating disc rotatably mounted on said pivot member on the rear face of said card, there being a peripheral, graduated calorie scale imprinted on said disc, said disc projecting beyond the latter extremity of said card, said latter extremity forming an index edge 10 for indicating positions on said scale; an elongated pointer pivotally mounted intermediate its extremities on said pivot member on the front face of said card, the first extremity of said pointer positioned to intersect the leader lines on said pages, the second extremity of said pointer extending outwardly over the projecting portion of said disc so that it may be gripped to the latter for rotating the pointer and the disc simultaneously; and a stop device on said card positioned 15 in the path of the first extremity of said pointer for stopping the movement thereof at a predetermined point.
